UNITED STATES PATENT OFFICE.

MAX FINGER, OF CHICAGO, ILLINOIS.

DESIGN FOR A CAKE OF SOAP.

59,416.

Specification for Design.

Patented Oct. 18, 1921.

Application filed October 26, 1920. Serial No. 419,739. Term of patent 14 years.

To all whom it may concern:

Be it known that I, MAX FINGER, a subject of the King of Rumania, residing at Chicago, in the county of Cook and State of Illinois, have invented a new, original, and ornamental Design for a Cake of Soap, of which the following is a specification, reference being had to the accompanying drawing, in which—

Figure 1 is a plan view of the design and Fig. 2 is a cross-section thereof.

I claim:—

The ornamental design for a cake of soap, as shown.

In testimony whereof I affix my signature.

MAX FINGER.
